James E. Scott,

UNITED STATES PATENT OFFICE.

JAMES E. SCOTT, OF LOUISVILLE, KENTUCKY.

DUST-EXCLUDING DEVICE FOR WINDOW-SASHES.

No. 806,582.

Specification of Letters Patent.

Patented Dec. 5, 1905.

Application filed June 20, 1905. Serial No. 266,193.

To all whom it may concern:

Be it known that I, JAMES E. SCOTT, a citizen of the United States, and a resident of Louisville, in the county of Jefferson and State of Kentucky, have made a certain new and useful Invention in Dust-Excluding Devices for Window-Sashes; and I declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is a side view of a portion of a window frame and sash having my invention applied thereto. Fig. 2 is a section on the line 22, Fig. 1. Fig. 3 is a perspective view of a corner of a window-sash having my invention applied thereto. Fig. 4 is a perspective view of a portion of the strip *d* without the extensions or lugs *p*.

The invention relates to dust-excluding devices for window-sashes; and it consists in the novel construction and combinations of parts as hereinafter set forth.

In the accompanying drawings, illustrating the invention, the letter *a* designates the sash way or groove of the window-frame *b*, and *c* a portion of the sash-frame adapted to move in said groove. The groove *a* of the window-frame is made larger than the sash-bar in cross-section in order to allow for the interposition of a metallic strip *d*. This strip *d* is designed to be made of spring sheet metal, but longitudinally in such wise as to provide a laterally-expanded portion or bead *e*, merging by its inner face into an inner plate *f*, having a terminal flange *g*, extending along its edge at right angles to its general plane. Externally the bead *e* is reentrant to provide a shoulder-bearing at *h* parallel to the flange *g* and from which an oblique spring-bearing wing-plate *k* extends, said wing-plate being a little broader than the inner plate *f*, so as to extend beyond the terminal flange *g* of said inner plate. The terminal flange *g*, as shown, terminates at each end a little short of the end of the plate *f*, and when seated in a longitudinal slot *m* of the sash-bar the ends of said terminal flange form stop-shoulders engaging the ends of said slot and serving to

hold the strip from moving lengthwise in relation to the sash-bar. When the sash is placed in the sashway, the spring-strips bearing by their exterior wings against the walls of the sashway serve not only to provide proper friction-contact to hold the sash in place and to prevent ingress of dust, but also to hold the flanges of the strips in the bearing-slots of the sash-bar. When, however, some fastening is desirable, the ends of the metallic strip may be provided with right-angular extensions or lugs *p*, which are perforated and secured to the ends of the sash-bar by suitable screws, as at *s*.

The spring bearing-strips having been connected to the sash-bar by seating the terminal flanges in the slots of said bar, the sash is placed in position in the window-frame. In this position the outer wings of the strips are designed to extend well into the sashway, usually beyond the edge of the sash-bar, and the bearing-shoulders *h* of the beads bear against the margins of the sashway. In this manner it is designed to provide an easy-moving sash which is protected by dust-proof spring-bearings which facilitate the adjustment of the sash in position in the sashway. Movement of the weather-strip inward is resisted by the contact of shoulder *h* with the window-framing, and movement thereof in the reverse direction or outward is resisted by the terminal flange *g*.

Having described the invention, what I claim, and desire to secure by Letters Patent, is—

1. In a dust-excluding device for window-sashes, the combination with a sash having a slot provided with end abutment-walls, of a sheet-metal strip having a longitudinal bead provided with a bearing-shoulder, an outer bearing-wing, and an inner plate having a terminal flange of less length than said inner plate, parallel to said bearing-shoulder, and having end stop-walls, said terminal flange engaging the slot of the sash, substantially as specified.

2. In a dust-excluding device for window-sashes, the combination with a sash having a slot provided with end abutment-walls, of a sheet-metal strip having a longitudinal bead provided with a bearing-shoulder, an outer bearing-wing, and an inner plate having a

terminal flange of less length than said inner plate, parallel to said bearing-shoulder, and having end stop-walls, said terminal flange engaging the slot of the sash, and said inner plate having perforated right-angle end lugs for engagement with the ends of the sash-frame, substantially as specified.

In testimony whereof I affix my signature in presence of two witnesses.

JAMES E. SCOTT.
